ARCH SUPPORT

August Mirenta, Tacoma, Wash.

Application April 9, 1935, Serial No. 15,364

10 Claims.

(Cl. 36—71)

My invention has for an object to provide an improved arch support in the form of an insole which may be inserted in a shoe to relieve various ailments of the human foot, such, for instance, as weak or flat foot, metatarsalgia, Morton's toe, and pronounced dislocation of the first metatarsal phalangeal articulation.

A more specific object of my invention is to provide an insole with a pad of novel form for supporting the anterior metatarsal arch. Heretofore it has been the practice to provide an elevation on the insole which rises to its highest point back of the metatarsal boneheads. I have found, however, that more satisfactory results are obtained by providing a metatarsal arch support which extends beyond the articulation of the metatarsal bones and the phalanges. My experience teaches that it is necessary to exert pressure on the metatarsal bones directly under their location and for this reason it is an object of my invention to provide a pad support for the metatarsal arch which extends rearwardly approximately to the articulation of the external and middle cuneiform bones with the second and third metatarsals.

Another object of the invention is to provide an insole with a flare adapted to lie under the first metatarsal bonehead, this flare being provided with a pad to support said bonehead. It is within the purview of my invention to form this pad as a separate element from the pad supporting the anterior metatarsal arch and also, if desired, to make these two pads integrally connected.

A further object of my invention is to provide an insole formed with either or both of the pads above described and having also a wedge shaped pad along the inner margin of the insole arranged to support the inner longitudinal arch of the foot.

Other objects and advantages of my invention will appear in the following description of two embodiments thereof and thereafter the novelty and scope of the invention will be pointed out in the claims.

In the accompanying drawing:

Figure 1 is a bottom plan view of an insole for the left foot, embodying one form of my invention, the skeleton of the foot being indicated in broken lines on the insole;

Fig. 2 is an edge view of the same looking from the right hand side of Fig. 1;

Figs. 3 and 4 are views in transverse section taken on lines 3—3 and 4—4 respectively of Fig. 1;

Fig. 5 is an end view looking from line 5—5 of Fig. 1 in the direction of the arrows;

Fig. 6 is a fragmental bottom plan view of another form of my invention; and

Fig. 7 is a view in section taken on line 7—7 of Fig. 6.

The structure shown in Figs. 1 to 5 inclusive comprises a main body 10 consisting of leather or other suitable flexible material contoured to fit within a shoe and extending from the heel to a point somewhat beyond the location of the metatarsal boneheads but slightly back of the toes. This body member has a flare 11 at one side which in use extends under the first metatarsal bonehead. The body 10 has a plane upper surface, but on its under side is beveled along the outer margin from the heel portion 12 around the toe portion 13 to and including the flare portion 11.

As a support for the metatarsal arch a pad 14 is applied to the under side of the body. This pad is preferably composed of rubber but may also be made of leather or other suitable flexible material, and it rises from a point substantially at the location of the cuneiform bones, preferably at the point where the exterior and middle cuneiform bones articulate with the second and third metatarsal bones. The pad 14 which is transversely convexed rises gently from said point and reaches its maximum height and width substantially under the metatarsal boneheads. Thence, it extends forward, tapering toward the main body of the insole and terminating slightly behind the location of the toes. This pad may take different forms depending upon the particular defect to be corrected. Over the pad is fitted a cover piece 15 of flexible material such as thinly skived leather which is cemented to the body piece 10.

Another insert 16 of suitable padding material is fitted between the cover 15 and the body 10 at the flare 11. The pad formed by this insert may be properly proportioned to the height of the pad 14 depending upon the conditions to be corrected. It will be understood that this pad serves to give proper support to the first metatarsal bonehead.

Along the inner margin of the insole a pad 17 of wedge shape in cross section may be inserted between the members 15 and 10 with the thin edge of the wedge disposed inwardly. The outer face of the wedge is preferably cut at an acute angle with respect to the plane of the member 10.

In use the insole is introduced into the shoe 55

with the plane surface uppermost and the pads exert pressure on, or, provide support for the foot through the flexible body 10. The pad 14 will provide a support for the anterior metatarsal arch and wherever necessary the additional pad 16 will provide a support for the first metatarsal bonehead. The longitudinal arch may be supported by the wedge shape insert 17. I wish it to be understood that my invention contemplates using the pads 12, 14, and 16 either separately or in combination and either or both of these pads may be combined with the support provided by the wedge shaped insert 17. It will be understood also that the cross section of the insert 17 may be varied as required.

While in the structures so far described I have referred to the pad 16 as a separate element from the pad 14, it will be obvious that in certain conditions these two pads could be integrally connected. Such a structure is shown in Figs. 6 and 7 in which parts substantially identical with those shown in Figs. 1 to 5 are given like reference numerals. It will be observed that in place of pads 14 and 16, I provide a single pad 14a with a lateral extension 16a adapted to support the first metatarsal bonehead. In other respects, the insole shown in Figs. 6 and 7 is the same as that previously described.

An important advantage of my improved support for the metatarsal arch lies in the fact that it extends substantially from the cuneiform bones to a point well beyond the metatarsal boneheads with the highest part of the support at said boneheads. This provides a rocking effect resulting in material comfort, and it assists in restoring normal posture.

While I have shown and described two embodiments of my invention these are to be taken as illustrative and not limitative and I reserve the right to make various changes in form, construction and arrangement of parts which fall within the spirit and scope of the following claims.

I claim:

1. A support for the human foot comprising a flexible insole provided with an elongated pad adapted to support the anterior metatarsal arch, said pad beginning at a point substantially at the location of the cuneiform bones of the foot and gradually increasing in thickness therefrom until it reaches its greatest thickness substantially at the articulation of the phalanges with the metatarsal boneheads.

2. A support for the human foot comprising a flexible insole provided with an elongated pad adapted to support the anterior metatarsal arch, said pad beginning at a point substantially at the location of the cuneiform bones of the foot and gradually increasing in thickness therefrom until it reaches its greatest thickness substantially at the articulation of the phalanges with the metatarsal boneheads and extending thence forwardly to a point slightly behind the toes and tapering to a feather edge at the latter point.

3. A support for the human foot comprising a flexible insole provided with an elongated pad adapted to support the anterior metatarsal arch, said pad rising gradually from a point substantially at the location of the cuneiform bones of the foot and reaching its greatest height substantially at the articulation of the phalanges with the metatarsal boneheads, said insole being also provided with a lateral flare adapted to lie under the first metatarsal bonehead of the foot, and a resilient pad at said flare.

4. A support for the human foot comprising a

flexible insole provided with an elongated pad adapted to support the anterior metatarsal arch, said pad rising gradually from a point substantially at the location of the cuneiform bones of the foot and reaching its greatest height substantially at the articulation of the phalanges with the metatarsal boneheads and extending thence forwardly to a point slightly behind the toes and tapering to a feather edge at the latter point, said insole being also provided with a lateral flare adapted to lie under the first metatarsal bonehead of the foot and a resilient pad at said flare.

5. A support for the human foot comprising a flexible insole provided with an elongated pad adapted to support the anterior metatarsal arch, said pad rising gradually from a point substantially at the location of the cuneiform bones of the foot and reaching its greatest height substantially at the articulation of the phalanges with the metatarsal boneheads and extending thence forwardly to a point slightly behind the toes and tapering to a feather edge at the latter point, said insole being also provided with a lateral flare adapted to lie under the first metatarsal bonehead of the foot and a resilient pad at said flare, the latter pad and the pad supporting the metatarsal arch being integrally connected.

6. A support for the human foot comprising a flexible insole provided with an elongated pad adapted to support the anterior metatarsal arch, said pad beginning at a point substantially at the location of the cuneiform bones of the foot and gradually increasing in thickness therefrom until it reaches its greatest thickness substantially at the articulation of the phalanges with the metatarsal boneheads and extending thence forwardly to a point slightly behind the toes and tapering to a feather edge at the latter point, and a pad along the inner margin of the insole adapted to support the inner longitudinal arch of the foot.

7. A support for the human foot comprising a flexible insole provided with an elongated pad adapted to support the anterior metatarsal arch, said pad beginning at a point substantially at the location of the cuneiform bones of the foot and gradually increasing in thickness therefrom until it reaches its greatest thickness substantially at the articulation of the phalanges with the metatarsal boneheads and extending thence forwardly to a point slightly behind the toes and tapering to a feather edge at the latter point, and a pad along the inner margin of the insole adapted to support the inner longitudinal arch of the foot, the latter pad being wedge shaped in cross section with the thin edge of the wedge disposed inwardly.

8. A support for the human foot comprising a flexible insole provided with an elongated pad adapted to support the anterior metatarsal arch, said pad rising gradually from a point substantially at the location of the cuneiform bones of the foot and reaching its greatest height substantially at the articulation of the phalanges with the metatarsal boneheads and extending thence forwardly to a point slightly behind the toes and tapering to a feather edge at the latter point, said insole being also provided with a lateral flare adapted to lie under the first metatarsal bonehead of the foot, a resilient pad at said flare, and a pad along the inner margin of the insole adapted to support the inner longitudinal arch of the foot, the latter pad being wedge

shaped in cross section with the thin edge of the wedge disposed inwardly.

9. An insole comprising a main body piece of flexible material having a substantially plane upper face and adapted to extend from the heel of the foot to a point well beyond the metatarsal boneheads, a central pad adapted to support the metatarsal arch and extending from a location substantially at the articulation of the exterior and middle cuneiform bones with the second and third metatarsal bones and rising thence to a maximum height at the articulation of the metatarsal bones with the phalanges and extending thence forward to a feather edge substantially behind the toes, said body piece being formed with a lateral flare, a pad at said flare in position to support the first metatarsal bonehead, said pads being secured to the under face of the body piece, and a covering of thin flexible material applied over the pads and secured to the body piece.

10. An insole comprising a main body piece of

flexible material having a substantially plane upper face and adapted to extend from the heel of the foot to a point well beyond the metatarsal boneheads, a central pad adapted to support the metatarsal arch and extending from a location substantially at the articulation of the exterior and middle cuneiform bones with the second and third metatarsal bones and rising thence to a maximum height at the articulation of the metatarsal bones with the phalanges and extending 10 thence forward to a feather edge substantially behind the toes, said body piece being formed with a lateral flare, a pad at said flare in position to support the first metatarsal bonehead, said pads being secured to the under face of the body 15 piece, a covering of thin flexible material applied over and secured to the main body piece, and an insert along the inner margin of the insole between the body piece and the cover piece adapted to support the inner longitudinal arch of the foot. 20

AUGUST MIRENTA.
